CLAIM

The ornamental design for a ribbed grab rail, as shown and described.

DESCRIPTION

FIG. 1 is a perspective view of the ribbed grab rail according to the present design;

FIG. 2 is an alternate perspective view of the ribbed grab rail of FIG. 1;

FIG. 3 is an end view of the ribbed grab rail of FIG. 1;

FIG. 4 is a right or left side view of the ribbed grab rail of FIG. 1;

FIG. 5 is a top view of the ribbed grab rail of FIG. 1;

FIG. 6 is a bottom view of the ribbed grab rail of FIG. 1; and,

FIG. 7 is a perspective view of the ribbed grab rail of FIG. 1, as installed using stanchions.

The claimed design is shown broken in the center for ease of illustration.
